(57) **CLAIM**

The ornamental design for an accent chair, as shown and described.

DESCRIPTION

FIG. 1 is a front, right, top perspective view of an accent chair, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 2;

FIG. 14 is an enlarged view of detail 14 in FIG. 3;

FIG. 15 is an enlarged view of detail 15 in FIG. 3;

FIG. 16 is an enlarged view of detail 16 in FIG. 3;

FIG. 17 is an enlarged view of detail 17 in FIG. 4;

FIG. 18 is an enlarged view of detail 18 in FIG. 4;

FIG. 19 is an enlarged view of detail 19 in FIG. 5;

FIG. 20 is an enlarged view of detail 20 in FIG. 5;

FIG. 21 is an enlarged view of detail 21 in FIG. 7;

FIG. 22 is an enlarged view of detail 22 in FIG. 8; and,

FIG. 23 is an enlarged view of detail 23 in FIG. 8.

The dash-dot-dash broken lines are for notating enlarged views and form no part of the claimed design.

1 Claim, 23 Drawing Sheets
